BOTTLED GOODS VENDING MACHINE

Clyde M. Parker, Kansas City, Mo., assignor to
The Selectivend Corporation, Kansas City, Mo.,
a corporation of Missouri

Application July 5, 1938, Serial No. 217,398

14 Claims. (Cl. 312—36)

This invention relates to a bottled goods vending machine, particularly for vending soft drinks of different flavors, and has for its principal object to provide a machine of this character constructed so that a purchaser may select a particular bottle or flavor.

Other important objects of the invention are to provide a machine of this character that is of simple operation; to provide a machine having a selector freely movable for successively carrying bottles into registry with a removal opening normally covered by a locked closure releasable upon insertion of a coin or token; to provide a structure wherein the closure is retained in closed position unless a selected bottle has been moved into registry therewith; to provide the machine with means for latchingly retaining the carrier from movement while the closure is open to prevent removal of other than the selected bottle; and to provide means for locking the coin mechanism from operation when the closure is open.

In accomplishing these and other objects of the invention, as hereinafter pointed out, I have provided improved details of structure, the preferred forms of which are illustrated in the accompanying drawings, wherein:

Fig. 1 is a perspective view of a vending machine constructed in accordance with the present invention, the closure for the bottle removal opening being shown in open position after it has been released by insertion of a coin in the vending mechanism to permit removal of a selected bottle.

Fig. 2 is a plan view of the machine with portions of the cover broken away and the vending mechanism housing in section to better illustrate the construction, the closure being shown in open position to permit removal of a bottle.

Fig. 3 is a similar view showing the closure in closed position.

Fig. 4 is a vertical section through the machine, a part of the bottle carrier being shown in section.

Fig. 5 is a detail perspective view of the bottle carrier and its actuating mechanism.

Fig. 6 is a cross-section through the machine on the line 6—6 of Fig. 4, but with the closure in closed position.

Fig. 7 is an enlarged detail section on the line 7—7 of Fig. 6, particularly illustrating the lever mechanism for locking the closure when a bottle is not in registry therewith.

Fig. 8 is a detail perspective view of the coin slide for effecting release of the latching lever.

Fig. 9 is a detail view of the lock for securing the lid in closed position on the cabinet.

Fig. 10 is a section through a modified form of machine.

Fig. 11 is a section on the line 11—11 of Fig. 10.

Fig. 12 is a detail perspective view of the door latching lever, and the guard lever shown in spaced relation.

Referring more in detail to the drawings:

1 designates a vending machine for bottled goods constructed in accordance with the present invention, and which includes a cabinet 2 having an insulated bottom 3 and side walls 4 to form a compartment 5. Extending across the compartment between the opposite side walls 15 are spaced partitions 6 and 7 having their upper edges terminating near the upper edges of the side walls and their lower edges spaced from the bottom 3 to connect with a horizontal partition 8. The partitions 6, 7 and 8 thus divide the compartment 5 into spaced refrigerant containing chambers 9 and 10 at the ends thereof, and connected by a passageway 11 provided under the horizontal partition 8. The chambers 9 and 10 are adapted to contain a refrigerant, such as ice, to cool water that passes into the compartment formed between the partitions 6 and 7, through openings 12 and 13 for cooling the bottled goods that are mounted in a carrier 14.

The carrier 14 includes a drum comprising upper and lower sections 15 and 16, having mating disk portions 17 and 18 provided with lateral abutting flanges 19 and 20. The sections 15 and 16 are secured in position by means of headed rods 21 extending through openings in the lower section and engaged in threaded bosses 22 of the upper section, the ends of the rods being peened, as at 23, to prevent loosening thereof. Extending inwardly of the respective disk portions 17 and 18, in the axes thereof, are hubs 24 and 25 for rotatable mounting on a spindle 26, the spindle 26 being carried on a flange 27 that is fixed to the central portion of the horizontal partition 8. In order to stabilize the carrier for rotation about the spindle 26, the partition is provided with rollers 28 engagingly supporting the disk portion 18 of the lower section near the periphery thereof, as best shown in Fig. 6. Formed in the disk portions of the respective sections are an inner and outer circular series of openings 29 and 30 for the disk portion 17, and 31 and 32 for the disk portion 18. The openings 29 and 30 are staggered relatively to each other and are of sufficient diameter to pass the bottles to be vend- ed, as indicated by the dotted lines 33 in Fig. 4.

The lower openings, however, are of smaller diameter to provide support for the bottoms of the bottles. The openings in the respective disk portions are preferably inscribed by flanges 34 and 35, the flanges 35 conforming to the diameter of the upper openings so as to receive and center the bottoms of the bottles over the lower openings as shown in Fig. 4. The peripheral edge of the upper disk portion has a series 10 of notches 36 corresponding to the bottle receiving openings, with alternate notches aligning with the openings in the outer circular series and the intermediate notches with the openings in the inner circular series as shown in Fig. 5.

15 The carrier thus described is intermittently rotated about the spindle by means of an actuating lever 37 which is pivoted at its lower end on a pin 38 carried by the arm 39 of a supporting frame 40 attached to the inner side of the partition 6. The frame 40 also includes an upper arm 41 provided with a slotted guide 42 in which the upper end of a lever 37 is guidably supported for limited movement. The lever 37 is normally retained in retracted position by an expansion 20 spring 43 having one end connected therewith and its opposite end to the frame 40. Pivotedly supported on a pin 44 projecting from the side of the lever arm at a point above the bottle carrier is a pawl 45 having a depending end 46 25 adapted to engage in one of the notches 36 when the lever is in retracted position and to effect advance of the carrier when the lever is pushed to the opposite end of the slot. To prevent retractive movement of the carrier, the adjacent side wall carries a pin 47 carrying a click 48 which also engages one of the notches 36.

The carrier is prevented from being advanced beyond the distance corresponding to the spacing of the notches by means of an arcuate lever 49 40 that is pivotally supported, as at 50, upon an ear 51 projecting from the frame 40. One end of the arcuate lever has a depending ear or lug 52 that is adapted to engage one of the notches 36 when the opposite end 53 of the lever is released from 45 engagement with a lug 54 projecting laterally from the lever arm 37 during initial movement of the lever arm. The arcuate lever 49 is urged in the direction of the carrier by means of a flat leaf spring 55 that is fixed thereto, as at 56, and 50 engages against the side wall of the cabinet opposite the click 48. Therefore, as soon as the lug 54 rides off the end 53 of the arcuate lever 49, the spring moves the ear 52 into contact with the periphery of the drum so that as soon as the next 55 notch registers with the ear 52 the spring 55 urges the ear into engagement with the notch, thereby stopping rotation of the drum and preventing coasting thereof. Upon return movement of the lever 37, the lug 54 thereon rides over the cam-shaped end 53 of the lever 49 to effect disengagement of the ear 52 with the notch. However, the depending lug 46 on the pawl 45 60 has engaged another of the notches to prevent any movement of the carrier.

The top of the cabinet is closed by an insulated cover or lid 57 that is pivotally secured to one of the side walls by hinges 58 and which is secured to the opposite side walls by means of a 65 key actuated lock 59 which engages a keeper 60 on the side wall of the cabinet as shown in Fig. 9.

In order to actuate the bottle carrier when the lid is in closed and locked position, the cover is provided with a plate 61 having a slot 62 therein 70 registering with a lateral lug 63 on the upper end

of the lever 37, and slidable in the slot 62 is a depending tongue 64 of an actuating member 65, the tongue 64 being of sufficient length to engage against the lateral lug 63 of the lever 37. The actuator includes an upper plate 66 slidably engaging the plate 61, and is kept in contact therewith by means of a pin 67 engaging the under side of the plate 61 and extending through the tongue 64, as shown in Fig. 4. The actuating member 65 also includes a knob 68 by which it 10 is readily manipulated to effect intermittent rotation of the carrier, as later described.

Formed in the lid or cover, in aligning registry with the openings 29-30 of the carrier, is a door opening 69 through which a selected bottle is withdrawn upon opening of a door 70. The door 70 is hinged, as at 71, to the frame 72 of the door opening 69, and is adapted to be swung from closing relation with the door opening to the position shown in Fig. 4, the door being provided with a suitable knob by which it may be readily opened upon release of door latching mechanism later described. The door is provided with windows 73 and 74 registering with the respective series of bottle openings in the carrier, and which are covered by transparent panels through which the labels on the caps of the respective bottles are observed as the carrier is intermittently rotated therebeneath upon reciprocation of the actuator 65.

Mounted on the cover, in spaced relation with the door 70, is a housing 75 containing a coin mechanism as indicated by the slide 76, the slide 76 being actuated upon insertion of a suitable coin (not shown) that is placed within a socket 77 that is formed in an end of the slide which projects from the housing 75, as in one form of well known coin operating mechanism. Pivotally mounted on the inner end of the slide is a pawl 78 adapted to swing in a retractive direction when the slide moves in a forward direction but which is rigidly supported by engagement with a stop 79 on the slide when the slide is pushed into the housing. The pawl 78 is pivoted to the underside of the slide on a pin 80 and 45 is normally retained in yielding engagement with the stop 79 by a spring 81 coiled about the pivot 80 and having one end 82 engaging against the pawl 78 and its opposite end 83 engaging against the pin 84 depending from the slide in spaced 50 relation with the stop 79. The side of the pawl adjacent the stop 79 is rounded, as at 85, to facilitate movement past a pin 86 on a door latching lever 87 upon retractive movement of the slide.

The lever 87 is in the form of a bell crank and 55 is pivotally mounted on a pin 88 within a space 89 formed within the interior of the lid of the cabinet, the lever being arranged so that the arm 90 carrying the pin 88 is in position to support the pin in an opening 91 in the bottom of the 60 housing 95 and the other arm 92 projects into camming engagement with a cam-shaped lug 93 depending from the closure. When the door is in closed position the lug 93 engages the lever arm 92 to swing the bell crank 87 in a counter-clockwise direction to move the pin 88 out of the path of travel of the pawl 78. However, when the door is opened a spring 94, which bears against the lever arm 92, moves the bell crank in the opposite direction to bring the pin 88 into 70 the path of the pawl 78 so that it is impossible to actuate the coin mechanism. If the slide 76, however, has been held in retractive position, the slide may be returned to its normal position since the pawl 78 is free to ride over the pin 88, but 75

when this occurs the slide cannot be returned to vending position as long as the door is open.

Also pivotally mounted within the space 89 on a pin 95 is an elbow lever 96, having a spring pressed arm 97 provided with a head 98 extending under the housing 75. The head 98 includes a latch-shaped lug 99 cooperating with an offset 100 to form a notch 101. Projecting laterally from the offset 100 is an extension 102 carrying a pin 103 that is movable in the opening 91 upon engagement of the pawl 78 to swing the elbow-shaped lever for releasing the door, as now to be described. The other arm 105 of the elbow lever 96 engages within the notch 106 of a hook-shaped keeper 107 which is carried on the under side of the door and projects through an opening 108 of the door frame.

When the door is open the bottle carrier is latched from rotation by a rocker arm 109 that is pivotally mounted in the space 89 on a pin 110 and has one end 111 provided with a lug 112 adapted to engage within the notch 101 to hold the elbow-shaped lever in unlatched position. The other end of the rocker arm carries a roller 113 that engages a cam track 114 on a latching member 115. The latching member is also pivotally mounted in the space 89 and has a lug 116 that is adapted to be moved into the path of travel of the bottle carrier actuating lever 37 when the door is opened. The rocker arm is swung on its pivotal mounting by means of an arm 117 that is fixed to the door and projects through a slot 118 in the door frame to engage a lateral extension 119 on the rocker arm. The rocker arm is normally urged to latching position by an expansion spring 120 having one end hooked to the arm 111 and its opposite end to a pin 105, as best shown in Fig. 2. It is apparent that when the door is unlatched the lug 112 will engage in the notch 101 to retain the elbow-shaped lever in disengagement with the keeper lug on the door. However, when the door is opened by grasping the knob 121 and swinging the door away from the cover, the arm 117 swings against the extension 119 to move the rocker arm in an anticlockwise direction (Figs. 2 and 3), to disengage the lug 112 from the notch 101 and to cause the roller to cam the arm 115 into position so that the lug 116 is in the path of the actuating lever 37 to thereby prevent rotation of the bottle carrier. The arm 115 is retained in this position as long as the door is open by means of a T-shaped rock lever 122 having a tongue 123 adapted to engage against a stop shoulder 124 of the arm 115.

The lever arm 115 and the T-shaped lever are normally urged to latching engagement by an expansion spring 125 connecting the respective levers, as best shown in Fig. 3. One end of the T-shaped lever carries an adjusting screw 126 that is adapted to be engaged by a depending lug 127 on the door which moves through a slot 128 of the door frame, as shown in Fig. 1, to disengage the tongue 123 from latching contact with a stop 124, thereby allowing the lever 115 to return to its normal position responsive to the spring 125. Upon closure of the door, the arm 117 moves away from the lateral extension 119 so that the spring 120 may return the lever 109 to normal position as shown in Fig. 3. When the door is closed the hook-shaped keeper engages the arm 105 to relatch the door and to move the elbow-shaped lever so that the pin 103 thereon is again in position to be engaged by the pawl 78.

In order to permit removal of only one bottle which aligns with the closure, the openings in the door frame are offset relatively to the openings in the carrier so that only one opening in the carrier aligns in any one position thereof. The door openings are substantially the same diameter as the openings in the bottle carrier and the frame 72 has fingers 129 depending therefrom at the respective sides of the necks of the bottles so that the bottles may pass therebetween, as best shown in Fig. 1.

In order to prevent opening of the door when a bottle is not in registry with one of the openings therein, I provide a safety mechanism, actuated by the bottle carrier, as now to be described. Pivotally suspended adjacent each of the lower openings in the bottle carrier on pins 131 are levers 132 having fingers 133 adapted to project through the openings but which are normally retained in depressed position when bottles are inserted in the carrier since the bottoms of the bottles engage the ends of the fingers as shown in Fig. 4. Fixed to the horizontal partition 8, at a point below the door, is a treadle-like lever 134 that is located in the path of travel of the fingers so that when it is engaged by a depressed finger, the treadle-like lever is depressed to effect movement of an arm 135 to withdraw a bolt 136 from locking engagement with the lug 127, the bolt 136 being supported in guides 137 and 138 and pivotally connected at its lower end with the arm 135 that projects from one end of the treadle-like lever. The treadle-like lever is normally retained in raised position to effect engagement of the bolt with the lug by a spring 139 that engages against the partition 8 and the under side of the treadle.

In order to prevent accidental latching of the elbow lever 96 by the rocker arm 109, I provide a safety or guard lever 140 that is pivoted alongside the arm 97 on a pin 141 so that the free end 142 of the lever 140 is in position to guard entrance to the notch 101 so as to prevent latching engagement of the lug 112 on the rocker arm. Therefore simultaneous slamming of the door 70 and actuation of the member 65 cannot cause latching of the elbow lever in door releasing position. To move the arm 140 out of guarding relation with the notch upon actuation of the coin slide, it is provided with a laterally extending arm 143 having a pin 144 projecting upwardly through the opening 91 to be engaged by the pawl 78 when the coin actuated slide 76 is projected into the machine upon the insertion of a coin. The pawl 78 thus engages the pin 144 to shift the arm 140 from guarding relation with the notch 101 prior to its engagement with the pin 103 which effects unlatching of the elbow lever as previously described. The arm 140 is normally retained in guarding position with the notch by a flat spring 145 fixed to the side thereof and which engages a pin 146 projecting from the lower plate of the cover or lid 57.

The operation of a machine constructed and assembled as illustrated in Figs. 1 to 9 inclusive, is as follows:

The cover 57 is unlocked and swung upwardly on the hinges 58 to permit access to the interior of the cabinet. The bottle carrier is then filled with bottles and ice is placed in the compartments 9 and 10 with sufficient water or meltage from the ice to pass through the openings 12 and 13 into cooling contact with the bottles. The cover 57 is closed and locked. When the cover is closed a bottle registers with one or the other

of the window openings 73 and 74. Assuming that the registering bottle is not of the flavor desired by a purchaser, he will move the actuator 65 to rock the lever 37 which carries the pawl 45, thereby moving the bottle carrier one space to bring the next bottle in the other circular series into alignment with the other window opening. If this is not the flavor desired, he will continue to reciprocate the actuator until a bottle of the desired flavor appears in one of the windows. During movement of the carrier, the spacing thereof is kept in accurate registry with the window openings by the arcuate-shaped arm 49 and the click 48 so that upon each full stroke 15 of the lever 37 the carrier is advanced exactly one space. When a bottle having the desired flavor is in registry with the opening the purchaser will place the coin or proper token in the pocket 71 of the slide and push the slide inwardly 20 so that the pawl engages the pin 103 to swing the elbow lever into latching engagement with the lug 112 and to disengage the arm 105 from the keeper on the door. The door may then be opened by grasping the knob 121. During opening 25 of the door the arm 117 thereon engages the extension 119 of the rocker arm 109 to effect swinging movement thereof which disengages the elbow lever 96 and allows the pin 103 to return to its normal position. This movement of the rocker arm 109 also cams the lever 115 into 30 position so that further operation of the actuator 65 is prevented. The lever 115 is latched in this position by the T-shaped lever 122 as long as the door is open. The slide 76 may have been 35 held in its retracted position; however, upon release thereof it is free to return to its normal position since the pawl is yieldable to pass the pins 103 and 186 with opening of the door, however, the bell crank lever 87 has shifted so that the pin 86 is in position to prevent further actuation of the slide 76. It is therefore impossible to again move the bottle carrier until the door has been closed.

Should the purchaser attempt to actuate the machine with the door closed, and have failed to move the carrier so as to bring a bottle in registry with one of the window openings 73 or 74, the finger 133 of the lever 132 will have been raised by the treadle-like lever so that the bolt 138 keeps the door 70 in locked position; however, when a bottle is in registry the finger 133 is engaged to depress the treadle for withdrawing the bolt so that the door may be opened.

Figs. 10 and 11 show a modified form of the invention which includes an elevating means for raising the bottle through the door opening so that the neck thereof may be more readily grasped by the purchaser. In this form of the invention plungers 147 and 148 are mounted in bearing openings 149 and 150 in the partition 8, the plungers being provided with downwardly opening bores 151 for slidably mounting the heads 152 of pins 153. Also mounted in the bore and engaging against the bottoms thereof and against the heads 152 are compression springs 154. The pins 153 engage the arm 155 of a rock lever 156, the rock lever 156 being mounted on a bracket 157 carried by the bottom of the cabinet, and which is adapted to be depressingly engaged by an arm 158 extending laterally from a rod 159. The rod 159 is guidingly supported in brackets 160 upon the wall of the cabinet and carries a head 161 engaged by a cam-shaped arm 162 projecting from the door 163. The rod is

normally retained in its upper position by a coil spring 164.

With the structure thus described, when the door is opened the arm 162 engages the head to move the rod 159 downwardly, thereby rocking the lever 156 and raising the pins 153. When the carrier is in proper position relatively to the door openings, only one of the plungers 147 and 148 will be effective since the other plunger engages against the bottom of the carrier as shown in Fig. 11, however, the spring 154 yields sufficiently to allow for movement of the arm 156. The plunger 147 which happens to align with the opening is moved therethrough to raise the bottle so that it may be readily grasped by its neck to effect withdrawal from the cabinet, otherwise the structure is substantially the same as that illustrated in the preferred form of the invention.

From the foregoing it is obvious that I have provided a vending machine for bottled goods whereby a purchaser may select a particular bottle or flavor, and which is constructed to prevent pilfering of more than the bottle which has been paid for. It is also obvious that the machine is constructed so that the purchaser is always sure of obtaining a bottle when he inserts a coin in the vending machine.

What I claim and desire to secure by Letters Patent is:

1. A vending machine of the character described including a cabinet having an article removing opening, a carrier having article receiving pockets, means rotatably supporting the carrier in the cabinet, an actuating lever reciprocably supported in the cabinet, a pawl on the lever having ratchet engagement with the carrier, for intermittently rotating the carrier, a closure for said opening, a latching lever movably supported in the cabinet to engage with said actuating lever, and a rock lever engageable with the latching lever and having a portion engageable with the closure to effect locking of the actuating lever upon opening of the closure.

2. A vending machine of the character described including a cabinet having an article removing opening, a carrier rotatably supported in the cabinet and having article receiving pockets successively registrable with said opening, a closure covering said opening, latch means engageable with the carrier and having operative connection with the closure to prevent rotation of the carrier upon opening of the closure, closure locking means, and means engageable with an article in one of said pockets for releasing said closure locking means.

3. A vending machine of the character described including a cabinet having an article removing opening, a carrier having pockets successively registrable with said opening, means rotatably supporting the carrier in the cabinet, an actuating lever pivotally mounted in the cabinet, a pawl pivotally carried on the actuating lever and having a portion engageable with the carrier, means slidably supported on the cabinet for operating the actuating lever, a latching member pivotally supported in the cabinet and having a portion projectable into the path of the actuating lever, a closure hingedly mounted on the cabinet for closing said opening, and an operating connection between said closure and the latching member to effect movement of the latching member into stopping relation with the actuating lever upon opening of the closure.

4. A vending machine of the character described including a cabinet having an article re-

- moving opening, a carrier having pockets successively registrable with said opening, means rotatably supporting the carrier in the cabinet, an actuating lever pivotally mounted in the cabinet, 5 a pawl pivotally carried on the actuating lever and having a portion engageable with the carrier, means slidably supported on the cabinet for operating the actuating lever, a latching member pivotally supported in the cabinet and having a portion 10 projectable into the path of the actuating lever, a rock lever having a portion engageable with the latching member, a closure hingedly mounted on the cabinet for closing said opening, and an arm on the closure engageable with the 15 rock lever to effect movement of the latching member into stopping relation with the actuating lever upon opening of the closure.
5. A vending machine of the character described including a cabinet having an article removing opening, a closure for said opening, a carrier having pockets successively registrable with said opening, means rotatably supporting the carrier in the cabinet, an actuating lever, means oscillatably mounting the actuating lever in the 20 cabinet, a pawl pivotally carried on the actuating lever and having a portion engageable with the carrier, a locking mechanism for the closure, a latching connection between the actuating lever and the locking mechanism, and manually operated means for releasing said locking mechanism.
6. A vending machine of the character described including a cabinet having an article removing opening, a carrier having pockets successively registrable with said opening, means rotatably supporting the carrier in the cabinet, an actuating lever pivotally mounted in the cabinet, a pawl pivotally carried on the actuating lever and having a portion engageable with the carrier, means slidably supported on the cabinet for operating the actuating lever, a latching member pivotally supported in the cabinet and having a portion 30 projectable into the path of the actuating lever, a rock lever having a portion engageable with the latching member, a closure hingedly mounted on the cabinet for closing said opening, an arm on the closure engageable with the rock lever to effect movement of the latching member into stopping relation with the actuating lever upon opening of the closure, a locking mechanism 35 for the closure, a latch connection between the locking mechanism and the rock lever, and manually operated means for releasing said locking mechanism.
7. A vending machine of the character described including a cabinet having an article removing opening, a carrier having pockets successively registrable with said opening, means rotatably supporting the carrier in the cabinet, an actuating lever pivotally mounted in the cabinet, a pawl pivotally carried on the actuating lever and having a portion engageable with the carrier, a latching member pivotally supported in the cabinet and having a portion projectable into the path of the actuating lever, a rock lever having a portion 40 engageable with the latching member, a closure hingedly mounted on the cabinet for closing said opening, an arm on the closure engageable with the rock lever to effect movement of the latching member into stopping relation with the actuating lever upon opening of the closure, and means having connection with the closure for retainingly engaging the latching member independently of said rock lever.
8. A vending machine of the character described including a cabinet, an article carrier, means rotatably supporting the article carrier in the cabinet, an actuating lever pivotally supported in the cabinet, a pawl on the actuating lever engageable with the carrier, a click in the cabinet engageable with the carrier to prevent retractive rotation thereof, a slide reciprocably supported on the cabinet, means on the actuating lever engageable by said slide whereby the actuating lever is moved in one direction upon actuation of the slide, and a spring connected with the actuating lever to move the actuating lever including said slide in the opposite direction.
9. A vending machine of the character described including a cabinet, an article carrier, means rotatably supporting the article carrier in the cabinet, an actuating lever pivotally supported in the cabinet to move the carrier in one direction, a pawl on the actuating lever engageable with the carrier, a click in the cabinet engageable with the carrier to prevent retractive rotation thereof, a spring connected with the actuating lever to return the actuating lever, and control means engageable with the carrier and actuated by the actuating lever to prevent coasting of the carrier.
10. A vending machine of the character described including a cabinet, an article carrier, means rotatably supporting the article carrier in the cabinet, an actuating lever pivotally supported in the cabinet, a pawl on the actuating lever engageable with the carrier, a click in the cabinet engageable with the carrier to prevent retractive rotation thereof, a slide reciprocably supported on the cabinet, a lug on the slide, means on the actuating lever engageable by said lug whereby the actuating lever is moved in one direction, a spring connected with the actuating lever to move the actuating lever including said slide in the opposite direction, and control means engageable with the carrier and actuated by the actuating lever to prevent coasting of the carrier.
11. A vending machine of the character described including a cabinet having an article removing opening, a carrier rotatably supported in the cabinet and having article receiving pockets successively registrable with said opening, a closure covering said opening, means hinging the closure along one side of the opening, latch means in the cabinet to engage said carrier, a lever having fixed pivotal support relatively to said cabinet and engageable with the latch means for preventing rotation of the carrier, and a cam on the closure engaging said lever to effect actuation of the latch means in preventing rotation of the carrier when the closure is opened.
12. A vending machine of the character described including a cabinet having a slot in the top thereof, an article carrier, means rotatably supporting the article carrier in the cabinet, an actuating lever movably supported in the cabinet and terminating short of the top of the cabinet, a pawl on the actuating lever engageable with the carrier, a slide reciprocably supported on top of the cabinet, lever engaging means on the slide and movable through said slot to abuttingly engage the lever whereby the actuating lever is moved in one direction upon manipulation of the slide, and a spring to move the actuating lever in the opposite direction.
13. A vending machine of the character described including a cabinet having an article removing opening therein, an article carrier rotatably supported in the cabinet and movable past said opening, a door hinged over the opening, means connected with the door for controlling

rotation of the article carrier, an actuating lever movably supported in the cabinet, a pawl on the actuating lever engageable with the carrier, a slide reciprocably supported on the cabinet and having lever engaging means whereby the actuating lever is moved in one direction to rotate the carrier when the slide is moved in one direction, spring means for moving the actuating lever including said slide in the opposite direction, and means acted upon by said control means for stopping the carrier when the door is opened.

14. A vending machine of the character described including a cabinet having an article removing opening, a carrier rotatably supported in

the cabinet and having article receiving pockets successively registrable with said opening, a closure covering said opening, lock means releasably securing the closure, a plurality of pivotally supported fingers mounted on the bottom of the carrier and having portions projectable into said pockets, finger actuating means having pivotal support within the cabinet below the carrier in registry with the article removing opening, and means connected with said finger actuating means for keeping the closure in locked position when a finger is moved into a pocket by said actuating means.
